(57) CLAIM

The ornamental design for a three pole connector, as shown and described.

DESCRIPTION

FIG. 1 is a perspective view of a three pole connector showing our new design;

FIG. 2 is a side view thereof, the opposite side view being a mirror image;

FIG. 3 is a bottom view thereof;

FIG. 4 is an end view thereof;

FIG. 5 is an opposite end view thereof;

FIG. 6 is a top view thereof; and,

FIG. 7 is an exploded perspective view thereof.

The broken lines in FIGS. 2-7 are included for the purpose of illustrating environmental structure only and form no part of the claimed design.
